UNITED STATES PATENT OFFICE.

HERBERT O. BRIGHAM, OF PROVIDENCE, RHODE ISLAND.

CONVERTIBLE SERVICE SYSTEM.

1,369,387.

Specification of Letters Patent. Patented Feb. 22, 1921.

Application filed May 5, 1920. Serial No. 379,124.

To all whom it may concern:

Be it known that I, HERBERT O. BRIGHAM, a citizen of the United States, residing at Providence, in the county of Providence, 5 State of Rhode Island, have invented certain new and useful Improvements in Convertible Service Systems, of which the following is a specification.

My invention relates to improvements in 10 convertible or interchangeable service-systems for stores, markets, restaurants, refectories, mess-halls, dormitories, barracks, lecture-halls, manufacturing plants, school buildings and other similar establishments 15 or institutions.

One object of the invention is to make available for more continuous use property or premises having a high rental value.

Another object of the invention is to provide an improved system for the more economical utilization of space in buildings devoted to merchandising or other service to the public.

Another object of the invention is to 25 adapt such a system for schools and colleges to provide for a more continuous use of available space in halls, dormitories or other buildings.

Further objects of the invention will appear from the description of the embodiment of my improved system set forth in 30 the following specification, which is illustrated by the accompanying drawings. In the drawings:

35 Figure 1 is a floor plan of a building showing my improved system applied to use therein for merchandising and food-service purposes;

40 Fig. 2, a longitudinal elevation of the same in cross-section;

Fig. 3, an end view of the same in cross-section; and

45 Figs. 4, 5, 6 and 7, enlarged detail views of various types of interchangeable units of furniture and fixtures for use with the system.

In certain circumstances many buildings or premises are in use only a part of the day for merchandising or other service to the 50 public. For instance, in restaurants and lunch-rooms the preparation of food takes place during the greater part of the day while its serving occurs only during specified hours. Usually the space reserved for 55 serving food to patrons occupies the front of the building where the rental charge is

relatively high and therefore a limited use of such space entails an economic loss. Likewise, in schools, halls, public buildings, and other institutions the space may be used 60 only a portion of the day or evening; while in dormitories, barracks, or the like, the space is only utilized at night and remains idle throughout the day.

To provide for a more complete utilization of such property or premises I have devised a method of dual usage which I have chosen to term a bi-service system. For the purpose of this description, property or premises shall be defined to include buildings of all kinds, floating property such as boats or ships, open air spaces, inclosed areas and all such other places as may be used, or available for use, for various and sundry purposes as herein described or otherwise suggested.

Stated briefly, my improved system contemplates the converting of the property or premises to different uses by the employment of interchangeable units of furniture, fixtures or other apparatus and appurtenances which may be easily and conveniently shifted from one location to another; for example, from a storage space to the place of use such as a store, restaurant, or other merchandising establishment, and back to storage again to make the space available for other uses by substitution of different apparatus.

For the purpose of illustrating one embodiment of the invention Fig. 1 shows the floor plan of a building suitable for use as a store or other merchandising establishment and convertible to other uses by means of my improved system. Referring to this 95 view of the drawings, the reference character A designates the main store or service space in the forward part of the building, usually fronting on a street or avenue to provide prominence of display for its windows and accessibility to customers or patrons. At the rear of the building, where the space is less valuable, or in another building adjacent thereto, I provide a storage space which is designated B in Fig. 1. 100 The rear storage room or space B may be of any convenient size and arrangement and is usually at least as large as the front room and preferably of greater area. The two rooms or spaces may be separated by a folding partition or may have a fire-wall between them in which are suitable openings

adapted to be closed by sliding or swinging doors or other suitable barriers arranged in the manner and for the purpose as later explained.

5 For the rapid and convenient interchange of store fixtures, furniture, seating facilities and other apparatus used in connection with the selling or serving of food, foodstuffs and other merchandise or commodities, or 10 for substitution of appurtenances employed for the purposes of recreation, exercise, study, sleep or work, I make use of mechanical transferring-means as next described. In one form, as shown in Fig. 1, these means 15 may consist in tracks, trolleys or runways designated 4 and trucks or carriers 5 travelable thereon. As here illustrated the tracks 4 are laid in parallel relation running from the storage space or rear room B to the front 20 room A through doorways 6 in the partition 2. These doorways 6 may be closed by swinging or sliding doors which are here shown in conventional form and designated 7.

25 The trucks or carriers 5 may consist of suitable platforms or chassis 8 mounted on rollers or wheels 9 which are preferably flanged, as shown in Fig. 5, to retain them in place on the parallel rails 10 of the tracks 30 4. The rails 10 are laid in grooves or runways 11, see Figs. 2 and 3, below the level of the floor in the room A, so that the platforms or chassis 8 of the trucks 5 will ride above or level with the flooring to bridge 35 the space in the runways when the trucks are wheeled into position in the front area. The flooring in the rear room B may or may not be raised above the tracks, this feature not being of importance in the storage space 40 for the trucks. If desired, suitable means may be employed for locking the trucks 5 in fixed relation on the tracks 4 in their position of use; but such means are not herein illustrated as they form no part of the present invention.

45 The cars or trucks 5 may embody any suitable design or structure with their platforms 8 adapted to carry the furniture, fixtures, or other apparatus as required. These 50 latter may be permanently affixed to the platforms 8, or may be attached thereto by suitable adjustable-clamps or fastening-means, not herein shown, to render them interchangeable thereon. As illustrated in Figs. 55 1, 2 and 3, the trucks 5 carry counters 12 which may contain shelving, bins or compartments for foodstuffs, merchandise or other products; or they may carry show cases constructed of glass in the form of 60 combination counters.

In the detail views, Figs. 4 and 5 illustrate the trucks 5 as mounting lunch-counters 14 having the usual seating-stools 15 and foot-rails 16 attached to their sides. In 65 Fig. 6 the platform 8 of the truck serves as

the flooring for combination desks and seats 17; or the truck might carry suitable tables and chairs. Fig. 7 shows still another modification of the truck or carrier 5 as arranged to carry a bed or cot 18. Various 70 and sundry further adaptations might be made to provide apparatus and appurtenances for other uses; for instance, opera-chairs, equipment for gymnasiums and similar devices could be carried on the trucks. 75

Referring again to Figs. 1, 2 and 3, a preferred plan of layout of the front room for display and merchandising purposes embodies a suitable arrangement of shelving on the side-walls as shown conventionally at 80 19. The area designated 20 may be utilized for a show window at the front of the store or fitted as an office or accounting-room. This space is shown as defined at one side by a fixed counter 21 which forms an entrance 85 lobby 22 communicating with a doorway 23 giving onto the street at the front of the building. In some instances I provide an exit doorway 24 at the opposite side of the building as indicated by dash lines. The 90 front space 20 when reserved for accounting may be separated from the main portion of the store by a counter 25 which serves for wrapping packages, as an adjustment desk, or for any other purpose in accordance with 95 the use to which the building is being applied.

The main area of the front room or store A is given over to the spur-tracks 4 which extend out through the doorways 6 in parallel relation to the side walls of the building. A convenient arrangement of the tracks comprises a single spur adjacent each side wall with space for the clerks or sales-people to stand behind the counters placed 100 on the tracks, and with pairs of other spurs arranged across the remaining space in the room. Preferably, the pairs or twin track-sections 4 are so spaced as to provide room 105 for the sales-people between two rows of opposite counters, and wider aisles 27 for customers between the pairs of counters. As illustrated in Fig. 1, a preferred arrangement of the tracks includes extensions 28 of the spur-sections 4 running into the storage-room B with suitable crossovers or switches 110 29 connecting the same. The track-extentions 28 lead into a lateral cross-track 30 at the rear of the room B and this latter is extended in loops 31 following around the 115 sides of the building and leading into the front spurs at 32. The space 33 within the loops 31 may be utilized for kitchens for the preparation of food to be supplied to the 120 lunch-counters on the trucks before they are 125 wheeled into the front room; or they may serve as transfer stations for loading the trucks with other commodities. In some cases the rear room B, which I term the "swing-room," may serve as the storage 130

space for merchandise, or the goods or provisions may be transferred thereinto by elevators, chutes, ramps or other conveyers arranged within the transfer spaces 33, as indicated in Fig. 1 by dotted-lines which show sets of elevators or hoists. In other cases the "swing-room" may be located in the basement or at a higher level than the main floor A, thus utilizing less valuable space. 10 With this latter arrangement the trucks or carriers 5 are transferred from the storage or supply base to the spur-tracks 4 by elevators, ramps, or the like operated with traveling-chains or belts.

15 The method of making use of my improved convertible service-system in one of its embodiments is substantially as follows: For an example of the working of the system we may consider the space A to be employed as a combination store and restaurant or lunch-room. Supposing the store to be for the sale of groceries or other food products, the heaviest requirements of trade would be in the early morning hours, say 20 between eight and eleven o'clock. During this period the spur-tracks 4 will be occupied by trucks 5 carrying counters or show-cases 12, as illustrated in Figs. 1, 2 and 3, the latter having been supplied with the goods 25 for sale before leaving the "swing-room" B. Now as midday approaches, say at eleven A. M., some of the counters 12 are withdrawn from the space A by moving the trucks into the "swing-room" B and other 30 trucks substituted in their place to provide lunch-counters 14 as illustrated in Fig. 4. The interchange of the fixtures may take place gradually, commencing at the center or side of the room A, and as the lunch trade 35 increases toward the noon hour more lunch-counters are provided until the whole space is occupied in this manner; or in some cases the wall counters may be left for displaying fruit, candy, cigars or other articles 40 adapted for sale to the lunch trade. As the luncheon hour draws to a close the lunch-counters 14 may be gradually withdrawn and replaced by the merchandise counters 12 until the store is once more adapted for 45 trade in other commodities. In this way the space in the front room A is utilized to maximum advantage throughout the whole day, and to extend its use into the evening a similar interchange of the merchandising 50 fixtures and food-serving units will adapt the space for restaurant purposes again.

In addition to this bi-service plan the system may be extended to cover a still further use of the space in the building 55 during the late evening. As an instance, we may consider the trucks or carriers as supplied with opera-chairs to provide seating-capacity for audiences at lectures or exhibitions such as moving-picture shows, 60 such extended use being particularly adapt-

ed for stores or buildings in small communities.

In adapting my improved system for use in school and college buildings, public institutions, industrial plants, dormitories, army 70 and navy barracks, mess-halls or the like, the day furniture may consist of desks and chairs and other apparatus carried on the trucks and displaced at certain hours by restaurant or lunch-room fixtures; while in 75 other cases the chairs or day furniture such as gymnasium apparatus may be displaced by beds or cots, the latter being stored in more compact arrangement in smaller quarters throughout the day. Various other 80 substitutions or interchange of furniture, fixtures, apparatus or the like may be made in this way, it being understood that such modifications of the system would fall within the intent and scope of the invention. In 85 adapting a building for such continuous use it would of course be necessary to supply adequate ventilation of its rooms, but this may be easily accomplished by various methods now in general use. 90

As will be observed from the above description, I have provided a novel and ingenious system for a more extensive or continuous use of property and premises whereby the economic value thereof may be increased. While I have herein explained the operation of the system more particularly in relation to the handling of food, it is to be understood that I do not wish to limit the invention in this respect since it may be applied to other purposes of merchandising or public service. Various modifications in the details of arrangement or construction of the apparatus may also be made without departing from the spirit or scope of the 105 invention, and therefore I claim broadly: 100

1. A convertible merchandising- or service-system comprising a building, a series of tracks, carriers travelable on the tracks 110 therein, and interchangeable units of furniture and fixtures carried by the carriers.

2. A convertible merchandising- or service-system comprising a building, a series of intercommunicating tracks therein, carriers travelable on the tracks, and interchangeable 115 units of fixtures carried by the carriers.

3. A convertible merchandising- or service-system comprising a building, a series of intercommunicating tracks therein, a second series of spur-tracks extending therefrom, carriers travelable on the tracks, and interchangeable units of fixtures carried by the carriers. 120

4. In a convertible merchandising- or service-system, a storage space, a separate 125 space for service, interchangeable units of furniture and fixtures for use in the service-space, and mechanical means for transferring the units back and forth between the spaces. 130

5. In a convertible merchandising- or service-system, the combination of a building divided into separate spaces, runways extending from one space to another, carriers travelable on the runways, and interchangeable units of furniture and fixtures carried by the carriers.

6. In a convertible merchandising- or service-system, the combination of a space 10 for use for service, a space for storage, a series of tracks arranged in interconnecting loops in the storage space, a series of track-extensions in the service-space, and carriers travelable on the tracks and adapted to 15 carry interchangeable units of furniture and fixtures.

7. In a convertible merchandising- or store-system, the combination of a main store having certain permanent fixtures, a 20 storage-space adjacent the main store, interchangeable units of furniture and fixtures adapted to be stored in the storage-space, and means travelable between the storage-space and store for transferring the inter-

changeable units in accordance with the use 25 to which the store is to be put.

8. In a convertible merchandising- or service-system, the combination of a service-room having a series of parallel tracks, a storage-space, a series of track-loops in 30 the storage-space communicating with the tracks in the service-room, cross-overs connecting said track-loops, trucks having wheels travelable on the tracks and interchangeable units of furniture and fixtures 35 carried by the trucks.

9. In a convertible service-system, the combination of a service-space, a swing-room, tracks arranged in depressed runways in the service-space, intercommunicating tracks in the swing-room, trucks travelable on the tracks and having platforms bridging the space in the runways, and interchangeable units of furniture and fixtures adapted to be carried by the trucks. 45

In testimony whereof I affix my signature.

HERBERT O. BRIGHAM.
